UNITED STATES PATENT OFFICE.

GEORGE T. WARWICK, OF SPRINGFIELD, MASSACHUSETTS.

WRAPPING-MACHINE.

No. 858,044.

Specification of Letters Patent.

Patented June 25, 1907.

Application filed November 21, 1905. Serial No. 288,485.

To all whom it may concern:

Be it known that I, GEORGE T. WARWICK, a citizen of the United States of America, and a resident of Springfield, in the county of Hampden and State of Massachusetts, have invented certain new and useful Improvements in Wrapping-Machines, of which the following is a full, clear, and exact description.

This invention relates to improvements in machines for automatically wrapping rectangular pieces, such as caramels or other confectionery, soap, yeast cakes, boxes and the like, with an entirely inclosing wrapper, and causing a sticking of the last folded portions of the wrapper, or other portions thereof, to make a satisfactorily secured package.

Another object of this invention is to construct and arrange the instrumentalities as to enable the machine entirely efficient for its purposes, to be of unusually simple and inexpensive construction, and one which will not require minuteness and closeness in the formation of the parts and the adjustments thereof.

In the attainment of leading objects of this invention, the piece to be wrapped is conveyed onto a progressively movable table relatively to which the wrapping sheet is brought,—the devices performing the successive wrapping operations being arranged at different positions successively reached by the piece on such table, so that the wrapping devices are distributed in comparatively open arrangement,—instead of being closely grouped,—and conducive to easier accomplishment of the ends to be attained. And in this machine triplicate movable folding boxes or receivers are provided on the progressive table, there being at least one for each of the mechanisms for partially wrapping the pieces, so that the wrapping operations, whether initial, intermediate, or final foldings on several pieces are simultaneously performed in the machine, thereby insuring capacity for turning out a maximum of completely wrapped and secured packages in a given time.

The invention consists in combinations and arrangements of devices or mechanisms and the constructions of certain of said devices and parts thereof, all substantially as hereinafter fully described and set forth in the claims.

In the description hereinafter given, the

articles to be wrapped are, for brevity and uniformity, herein termed "pieces."

In the drawings,—Figure 1 is a plan view of the complete machine, showing the receiving tray and a quantity of wrapped packages in regular rows thereon,—a portion of the feed conduit for the pieces, and the feeding table at an upper part of the machine, being absent from this view. Fig. 2 is a vertical sectional view and elevation of parts seen at and beyond the plane of section represented in line 2—2, Fig. 1, and on a somewhat larger scale. Fig. 3 is a plan view of parts as seen below the line 3—3, Fig. 2. Fig. 4 is a perspective view showing a portion of the progressive table, one of the folding boxes, the plunger for performing the first wrapping operation, and a portion of the wrapping, feeding, and severing mechanism. Fig. 5 is a vertical sectional view through substantially the same parts represented in Fig. 4. Fig. 6 is a perspective view showing the piece and the wrapper partially folded, as accomplished by the devices illustrated in Figs. 4 and 5. Figs. 7 and 8 show mechanisms for bringing the wrapper about the tubular piece, and with the ends thereof projecting beyond the opposite ends of the piece,—Fig. 9 representing the last named condition of the wrapper relatively to the piece. Fig. 10 is a perspective view showing a part of the mechanism for folding the endwise projecting portions of the wrapper inwardly against the opposite ends of the piece. Fig. 11 is a perspective view showing the mechanism for tuck folding side portions of the endwise projecting portions of the wrapper against the ends of the piece,—Fig. 12 being an elevation of the same. Fig. 13 is a perspective view showing the nearly completed wrapping of the package, which condition is brought by the last mentioned mechanism. Fig. 14 is a perspective view showing a portion of the gummer, and indicating the manner of its action on the remaining unfolded flaps of the wrapper. Fig. 15 is a vertical sectional view, as taken on the line 15—15, Fig. 3, more particularly illustrating the discharge of the wrapped pieces and their delivery to the receiving tray. Fig. 16 is a perspective view of the completely wrapped package.

Similar characters of reference indicate corresponding parts in all of the views.

This invention includes a conduit A for

the rectangular pieces *a* to be wrapped, delivering to mechanism for performing the first portion of the wrapping operation; and comprising a detent or yielding support *B* so that only one piece at a time may be delivered; means for forwardly feeding the wrapping paper, comprising a support *c* for a paper supply roll *C*; intermittently operating sheet-advancing mechanism and intermittently operating paper severing mechanism to cut off an advanced portion of the paper suitable for making the wrapper; an intermittently progressive table *D* having one or more upwardly open trough-shaped folding boxes *E* thereon; and means for intermittently advancing the table; also a reciprocatory plunger *F* having a recess *20* in its lower end corresponding to the shape and size of the piece to be wrapped, and co-operative with the trough-shaped folding box to force the piece with the wrapper into the box and to upturn the opposite sides alongside the piece and with the end portions of the paper projecting beyond the opposite ends of the piece, and the upturned sides projecting above the top of the folding box and the piece, therein, (as seen in Figs. 2, 4, 5 and 6); a pair of slidable folders *G*, *G*² located at opposite sides of the course of intermittent motion of the table, and folding box thereon, and having means for moving them successively across and close to the top of the box and the piece to be wrapped, and for bringing the wrapper to tubular condition, as represented in Figs. 7 and 9; and also co-operative with the movable table and folding box is a plunger *H* which may be advantageously located for its vertical movements in a line between the opposite horizontal top folders *G*, *G*², which plunger has downwardly projecting extensions separated by a space slightly greater than the transverse dimension of the piece to be wrapped and operable to engage the overlapped end portions of the wrapper at the plane of the top of the piece and oppositely endwise beyond the same, to downwardly tuck such portions, and with them triangular portions of the sides of the wrapper which are extended endwise beyond the piece, against the opposite ends of the piece, as shown in Fig. 10.

Each trough shaped folding box on the progressively movable table has through both of its opposite sides apertures separated by a distance about equal to the length of the "piece", at or about the plane of the bottom of the trough-shaped box, and folders or tuckers *J*, *J*² are provided to work through these apertures for making the side tucks, which close from opposite corners against each end of the piece, as represented in Figs. 12 and 13.

At a location suitably beyond that of the last mentioned tuck formers or folders and 65 relatively to which the table with the folding

box and nearly wrapped piece therein are brought, is a reciprocatory gummer *K* having separated depending gummer members in conjunction with which gum supplying mechanism *L* is provided; and said gummer is operable to straddle about the piece so far wrapped, as shown in Figs. 13 and 14, and to deposit patches of adhesive on the remaining unfolded endwise projecting bottom portions of the wrapper, as shown in Fig. 15, 75 so that when these gummed portions of the wrappers are folded against the ends of the package the wrapper will be stuck and thereby secured in its closed condition.

Each trough shaped folding box is constructed with a rectangular aperture *22* through its bottom provided at which is a sliding horizontal plate or movable bottom *R* having a rectangular aperture *23* at a portion thereof which is normally outside of the folding box; and the table has a rectangular aperture *24* vertically therethrough and directly below the aperture in the folding box bottom, so that all of these apertures may, when the slidable bottom is properly moved, 80 establish a passage or opening down through which the wrapped pieces may be discharged; and for the purpose of positively insuring the expulsion of the wrapped pieces, a plunger *M* is provided with means for imparting thereto 85 its descending movement at the proper time to downwardly push the packages.

Below the delivery aperture in the progressively movable table is a vertical chute or package receiving opening *d* communicating with a horizontal package conduit *e* adjacent which is a tray or receiving table *N* onto which the packages may be successively pushed,—a periodically acting pusher *O* being provided therefor,—and after a row, including a predetermined number of the packages, has been formed on the receiving tray or table, another pusher *P* operates to move them in a line at right angles to their course of entrance onto the tray to leave space for a new row of the packages to be formed on the tray.

A description of the machine in respect of the particular design and specific form and construction of the individual devices thereof will now be given, it being at this time stated that a machine including less than all of the mechanisms shown, and to be particularly described, or in which some of the mechanisms are of modified character may be employed 115 under some circumstances with entirely satisfactory results.

30 represents the machine frame comprising the stationary table like top 32 for supporting all of the fixed and movable portions 120 of the several mechanisms.

Approximately at the middle portion of the frame top is a fixed upstanding short stud 33 having a comparatively large affixed horizontal disk 34 at its upper end, surrounding 130

which stud below the disk is a sleeve hub 35 (Fig. 2) of the progressive table D which is circular, wider than the frame disk 34 and has at regular intervals on and distributed around its marginal portion, the upwardly open trough-shaped folding boxes E, the lengths of which are at right angles to lines radial of the circular table.

36 represents the driving shaft of the machine horizontally mounted in suitably elevated journal bearings and has a driving pulley 37 and by bevel gearing, 38, imparts continuous rotary motion to a vertical shaft 39 near the lower portion of which is a cam 40 co-operating with the rolls of a cam-rod 42 which is jointed to the horizontal swinging pawl carrier 43, the spring pressed pawl 44 of which successively engages in the ratchet-like teeth 45 of the rotary table, and set at eightths at the edge thereof, to intermittently move the table eightths of rotations, such pawl having retracting movements in each rotation of the shaft 39 to engage a new tooth of the table; and eight of the trough-shaped folding-boxes E are provided to correspond to the eight propulsion teeth of the circular table D.

The point in the machine at which the first wrapping operation is performed is at the right hand side, Fig. 3, adjacent the location of the paper supply C.

The paper is led off from the supply roll onto the shelf 47 at about the plane of the tops of the folding boxes, under a guide roll 48, and between a pair of feed rolls 49 and 50. One of the feed rolls 49 has a spur gear 52 affixed on its journal shaft with which a mutilated gear 53 meshes to periodically cause feeding movements of the said pair of feed rolls. The mutilated gear 53 is affixed on a horizontal shaft 54, which by bevel gearing represented at 55 derives continuous rotary movement from the aforementioned vertical shaft 39.

45 The paper being inwardly fed at the proper time when one of the folding boxes E is in proper position relatively to such paper in feed, the cutting off action is imparted by the blade or shear 56, suitably guided for its vertical movements, which movements are imparted thereto by the pitman 57 pivotally connected to the blade and to a crank or eccentric stud 58 carried on one of the feed roll journals.

55 The feed chute or conduit A for the pieces leads from a feed or supply table 60 suitably elevated above the top of the machine frame to a position slightly above the first position of each folding box, this chute having proper inclination to impart a gravitational feed to the pieces, its delivery end portion, however, being more or less nearly horizontal, as shown in Fig. 2, and in order that the pieces may be stopped and squared directly over

the folding box, a vertical stop blade is provided, as shown in Figs. 2, 4 and 5.

In order that the pieces may be carried, one at a time, only, into folding boxes successively in position therefor, and only as positively forced, the detent B is provided adjacent and as a continuation of the base of the feed conduit A, and is shown as consisting of an annular piece, one member of which forms a counterweighting lever so that the piece supporting member will normally remain in a horizontal position, as shown in Figs. 2 and 4.

The plunger F, recesses to straddle the piece, is carried on a plunger frame 64, this plunger frame being made unitary with a vertical slide bar 65 movable in the slides 66 carried by upright portions of the frame, and the positions and movements of this plunger frame are controlled by the path or groove cam 67, and cam roll 68 in engagement therein, as seen in Figs. 2 and 15. The plunger F performs the operation clearly illustrated in Figs. 5 and 6. Now on the upward retiring of the plunger F, the rotary table is advanced one-eighth of a rotation, carrying the folding box with the piece and wrapper therein to the second position at

which are located the top folders G and G² which folders have their operations in quick succession for the wrapping results perceived in Figs. 7 and 8.

The outer folder G is carried as a part of the slide bar 69 horizontally movable through the slide way 70, and the movements of this slide bar are imparted positively in one direction by a cam 72 on the rotary shaft 73 through connection by gearing, indicated at 74, with the aforementioned vertical shaft 29,—while the outwardly retracting movement of this slide bar is caused by the spring 75. The inner folder G² of the pair operable at the position 2 and in a suitable slideway 71, is actuated by a toggle-like bar 77 arranged in an inclined position and pivotally connected to the plunger frame and the slide G² so that the vertical reciprocation of the plunger frame will impart the horizontal reciprocations of the sliding folder G².

The wrapper, brought to tubular condition represented in Figs. 8 and 9 is, before the departure of the folding box from position 2, also further folded to condition represented in Fig. 10, and by the action of the plunger H having a recessed bottom assists to straddle over the piece and fold down the tops of the end portions of the wrapper and the triangular portions of the wrapper sides; and this plunger H is made in the form of a simple bar or block attached to and depending below the plunger frame, the descent of which quickly follows the folding action of the folder G².

The table having its further one-eighth movement brings the folding box to the position

3, whereat the tuck folders J, J² have their operations, bringing the piece to the nearly wrapped conditions shown in Figs. 12 and 13.

It will now be particularly noticed that 5 each of the trough-shaped folding boxes E has in both side walls thereof the pairs of apertures 80, 80, separated by a distance approximately that of the length of the piece, and the tuck folders, J, J² have carried on 10 the slide bars 82, which move in ways 83 therefor, folder or tucker wings 85, 85, at their inner ends and in separation so that in moving through said apertures 80 and into the space in the trough-shaped folding box, they 15 will embrace the piece and effect the tucking of the opposite endwise or extending portions of the wrapper against the ends of the piece, one tuck overlapping the other, as represented in Fig. 13; and for the purpose 20 of most nicely performing these operations, the extremities of the tucker wing are rounded or beveled, as represented in Figs. 11 and 12.

The slide carrying the tucker J having its movements inwardly before the other tucker 25 has its operation, is actuated by the cam 86 on a horizontal shaft 87, which by gearing at 88 is driven from the shaft 73, which in turn is driven from the vertical shaft 39, the spring 90 retracting the slide after this 30 positive cam imparted movement.

The inwardly located tucker J² is operated in a similar manner to the folder G², that is by a toggle like inclined bar 92 pivotally connected both to the tucker slide 82 and to 35 the plunger frame 64.

The rotary table advancing with the folding box to position 4, brings the piece nearly wrapped, as represented in Fig. 13, subject to the action of the gummer K, which consists of a fork-shaped frame pivotally hung at 96 in depending ears of the plunger frame, and is provided with an angularly bent lever arm 97 coöoperating with which is an affixed abutment 98 upstanding above the top 32 of the machine frame. When the plunger frame is moved downwardly, the impingement of the roller provided extremity of the lever extension 97 by impingement against the approximately horizontal portion of the 40 abutment 98 causes the gummer K to be swung to its vertical position for its gumming action, and in the continued downward movement of the plunger frame, the gummer and its extension lever, the extremity of the 45 latter has a sliding contact against the vertical side of the abutment 98 for constraining the gummer in its vertical position. The returning upward movement of the plunger frame carrying the gummer at the bottom 50 therewith, finally brings the extremity of the extension lever 97 to the top of the abutment, whereupon the gummer retracting spring 99 becomes effective to swing the 55 gummer to its inclined position shown in 60

Fig. 2, so that its gumming ends have an 65 impingement peripherally against the gumming rolls 100, which are partially submerged in the gum box 102; and such impingement of the gummers against the edges of the gumming rollers is effective to cause partial 70 rotation to such rollers so that fresh gum supplying surfaces are brought to the points of contact of the gummers. The progressive table now carrying the folding box and its 75 nearly wrapped piece therein to the position 5, at that point there is no mechanism for coaction on the wrapper, although at this point crimping or labeling devices might be located, if desired. The table now having its next step to carry the box around to position 6, it will be perceived that the cam 103 is coöperated with by the sliding bottom closure R for the folding box, so that when the folding box reaches position 7, which is three-quarters around from position 1, the 80 slide bottom R is in its inward position so that the aperture therein leaves the bottom of the folding box open, and whereby now the piece with the wrapper in the condition shown in Fig. 14 may be downwardly discharged through the bottom of the box and through the aperture thereon in a marginal portion of the rotary table, and into the vertical receiver d, it being clearly understood 85 that the action of the projecting end portions of the wrapper in the plane of the bottom of the piece relatively to the opposite margins of the hole through the folding box bottom result in the closing of the gummed portions 90 of the wrapper against the end of the package. 95

The plunger M carried by the plunger frame has its line of vertical movement at position 7, and positively forces the piece 100 downwardly into the receiver opening d.

The pusher O, which forces the pieces 105 fully wrapped as shown in Fig. 16 horizontally through the conduit e into the tray N, is operated by an angular lever or pulley crank 104 with which a downwardly extending rod 105, carried by the plunger lever, has a pin and slot engagement. The forcing pressure by the pusher O against the wrapped pieces being in the line of the gummed ends, and causing one piece to be in firm contact 110 endwise against the ends, precludes any liability of the gummed final flaps from opening 115 away from the ends of the package.

The pusher P which has its movement in 120 the tray at right angles to the line of entrance of the pieces into the tray, is given this pushing movement once in a given number of feedings of pieces into the tray,—say once every time a row of 16 becomes complete,—by means of lever 107 intermediately pivotally mounted on the frame 125 top 32 having one member thereof engaged with the pusher P, and having the inclined nose of the other member thereof in the

path of, and to be impinged against by a stud or roller 108 on the face of the horizontally mounted spur gear wheel 109, which is in mesh with the smaller spur gear 110 affixed 5 on the sleeve-like hub 35 of the rotary table. The retracting movement of the pusher P and lever 107 engaged therewith is accomplished by the spring 101, Fig. 1.

In the movement of the table and folding 10 box to position 8, the inner extremity of the 15 slideable closing bottom R for the folding box is in impingement against the fixed cam 112, whereby such bottom is forced to its normal outer and folding box aperture-closing position.

While in the foregoing detail description reference has been made to an individual folding box, and to the mechanisms with which it is successively brought for coaction 20 therefor, it is clearly to be understood that each one of the series of eight or other number of the folding boxes, which might be provided to similar receiver pieces and wrappers thereinto, and the machine is accomplishing 25 parts of package making operations simultaneously at several points in the orbit of the boxes so that at the time the blank or piece is fed to one box, that is at the time the blank and pieces are being fed to and are being 30 partially wrapped at one box, the top folding of a wrapper about another piece is being performed at the box next in advance, while in the box still further in advance the tucking folders are made, and this during the 35 time the gumming is being performed at the box in a still further advancing position; and the final wrapping and discharging of the 40 fully wrapped piece is done simultaneously with the folding operations being performed on several other pieces intermittently progressing to the place of discharge.

I claim:

1. In a wrapping machine, a movable table, having a trough-like folding box thereon, constructed with an apertured bottom, and a movable closure therefor, means respectively located adjacent the path of the box for imparting wrapping operations upon a wrapping sheet, and about a piece to be wrapped, which piece and sheet conducted to and carried by the box, means for displacing said movable closure to leave the aperture at the bottom of the folding box open, and means for forcing the wrapped pieces from the box through the said aperture.

2. The combination with a horizontal rotary table having an upwardly open trough-like folding box thereon, and means for imparting intermittent progressing movements 60 to the table and box, of means for bringing a wrapper adjacent a given position, to which the folding box is brought by the table, across the top of the box, means for conducting a piece to a position over the box and 65 wrapper, a plunger having a reciprocating

movement vertically relatively to the position assumed by the folding box, the wrapper and the piece, and operable for forcing the piece and wrapper into the box, upturning the wrapper sides, and further means located adjacent the path of the box, and to which the latter, with the partially wrapped piece, is conveyed, operable to fold upwardly projecting side portions of the wrapper horizontally onto the top of the piece.

3. The combination with a horizontal rotary table having an upwardly open trough-like folding box thereon and means for imparting intermittent progressing movements to the table and box, of means for bringing a wrapper adjacent a given position to which the folding box is brought by the table, across the top of the box, means for conducting a piece to a position over the box and wrapper, a plunger having a reciprocating movement vertically relatively to the position assumed by the folding box, the wrapper and the piece, for forcing the piece and wrapper into the box, upturning the wrapper sides, further means located adjacent the path of the box and to which the latter, with the partially wrapped piece, is conveyed, operable to fold upwardly projecting side portions of the wrapper horizontally onto the top of the piece, and a second plunger reciprocating vertically across the circular path of the box, suitably removed from the first named plunger, and operable to tuck the end extensions of the upper horizontal portions of the wrapper against the ends of the piece.

4. The combination with a horizontal rotary table having an upwardly open trough-like folding box thereon and means for imparting intermittent progressing movements to the table and box, of means for bringing a wrapper adjacent a given position to which the folding box is brought by the table across the top of the box, means for conducting a piece to a position over the box and wrapper, a plunger having a reciprocating movement vertically relatively to the position assumed by the folding box, the wrapper and the piece, for forcing the piece and wrapper into the box, upturning the wrapper sides, further means located adjacent the path of the box, and to which the latter, with the partially wrapped piece, is conveyed, operable to fold upwardly projecting side portions of the wrapper horizontally onto the top of the piece, a second plunger reciprocating vertically across the circular path of the box, suitably removed from the position of the first named plunger, and operable to tuck the end extensions of the upper horizontal portions of the wrapper against the ends of the piece, and means located adjacent the path of the box oppositely operable to tuck extended side portions of the wrapper against the end or ends of the piece.

5. The combination with a horizontal

tary table having an upwardly open trough-like folding box thereon and means for imparting intermittent progressing movements to the table and box, of means for bringing a 5 wrapper adjacent a given position to which the folding box is brought by the table across the top of the box, means for conducting a piece to a position over the box and wrapper, a plunger having a reciprocatory movement 10 vertically relatively to the position assumed by the folding box, the wrapper and the piece, for forcing the piece and wrapper into the box, upturning the wrapper sides, further means located adjacent the path of the box 15 and to which the latter, with the partially wrapped piece, is conveyed, operable to fold upwardly projecting side portions of the wrapper horizontally onto the top of the piece, a second plunger reciprocating vertically 20 across the circular path of the box suitably removed from the first named plunger, and operable to tuck the end extensions of the upper horizontal portions of the wrapper against the ends of the piece, means located adjacent a further point in the path of the box oppositely operable to tuck extended side portions of the wrapper against the end or ends of the piece, and means for folding the final endwise extended portions of the 25 wrapper against the end of the package.

6. The combination with a horizontal rotary table having an upwardly open trough-like folding box thereon and means for imparting intermittent progressing movements to the table and box, of means for bringing a 30 wrapper adjacent a given position to which the folding box is brought by the table across the top of the box, means for conducting a piece to a position over the box and wrapper, a plunger having a reciprocatory movement 35 vertically relatively to the position assumed by the folding box, the wrapper and the piece, for forcing the wrapper and piece into the box, upturning the wrapper sides, further means located adjacent the path of the box and to which the latter, with the partially wrapped piece, is conveyed, operable to fold upwardly projecting side portions of the wrapper horizontally onto the top of the piece, a second plunger reciprocating vertically 40 across the circular path of the box suitably removed from the first named plunger, and operable to tuck the end extensions of the upper horizontal portions of the wrapper against the ends of the piece, means located adjacent a further point in the path of the box oppositely operable to tuck extended side portions of the wrapper against the end or ends of the piece, and means for gumming the final endwise extended portions of the 45 wrapper against the end of the package.

7. The combination with a horizontal rotary table having an upwardly open trough-like folding box thereon and means for imparting intermittent progressing movements to the table and box, of means for bringing 50

a wrapper adjacent a given position to which the folding box is brought by the table across the top of the box, means for conducting a piece to a position over the box and wrapper, a plunger having a reciprocatory movement 55 vertically relatively to the position assumed by a folding box, the wrapper and the piece, for forcing the piece and wrapper into the box, upturning the wrapper sides, further means located adjacent the path of the box and operable to fold upwardly projecting side portions of the wrapper horizontally onto the top of the piece, a second plunger reciprocating vertically across the circular path of the box suitably removed from the first named plunger rod, and operable to tuck the end extensions of the upper horizontal portions of the wrapper against the ends of the piece, means located adjacent a further point in the path of the box oppositely 60 operable to tuck extended side portions of the wrapper against the end or ends of the piece, means for gumming endwise extended portions of the wrapper, and means for folding the final endwise extended portions of the 65 wrapper against the end of the package.

8. The combination with a horizontal rotary table having an upwardly open trough shaped folding box thereon, and means for imparting intermittent progressing movements to the table and box, of horizontal slides located adjacent the path of the box, at the level of the top thereof, having means for moving them crosswise of the box, and operable to fold upwardly projecting side 70 portions of the wrapper horizontally onto the top of the piece, and a plunger located, and having reciprocatory movements vertically adjacent said slides, and operable to tuck the end extensions of the upper horizontal portions of the wrapper against the ends of the piece.

9. The combination with a horizontal rotary table having thereon an upwardly open trough shaped folding box, and means for imparting intermittent progressing rotational movements to the table and box, of horizontal slides located adjacent the path of the box at the level of the top thereof, having means for moving them crosswise of the box, and operable to fold upwardly projecting side portions of the wrapper horizontally onto the top of the piece, a plunger located and having reciprocatory movements vertically adjacent 75 said slides, and operable to tuck the end extensions of the upper horizontal portions of the wrapper against the ends of the piece, and means located adjacent a further point in the path of the receiver for tucking endwise extended side portions of the wrapper against the ends of the piece.

10. A horizontal rotary table and means for intermittently imparting thereto progressive rotational movements, and said table having thereon at regularly spaced intervals

a plurality of upwardly open trough shaped folding boxes, a series of mechanisms having fixed locations adjacent the circular path of the boxes, and independent of which the table has its progressive movements, relatively to which the folding boxes are successively and respectively moved, viz: means for feeding a wrapper to one of the positions to which the boxes are successively brought, and means for conducting a piece to be wrapped above the wrapper and to such position of the box and a vertically reciprocating plunger for forcing the piece and wrapper downwardly into the box; slides for folding upstanding side portions of the wrapper horizontally onto the top of the piece, a second vertically reciprocating plunger for inwardly folding top endwise extending portions of the wrapper against the ends of the piece; and opposite horizontally sliding tuckers for folding endwise projecting side portions of the wrapper against the ends of the piece.

11. A table and means for imparting thereto substantially progressive movements, and said table having thereon at regularly spaced intervals a plurality of folding boxes, having apertures through their bottoms which are also continued through the table, and movable closures for said apertures, a series of mechanisms relatively to which the folding boxes are successively and respectively moved, viz: means for feeding and receiving a wrapper, and means for conducting a piece to be wrapped adjacent a folding box and above the wrapper, and a plunger for forcing the piece and wrapper downwardly into the box; means for folding upstanding side portions of the wrapper horizontally onto the top of the piece, and a plunger for inwardly folding the top portions of the wrappers against the ends of the piece; and opposite horizontally operable tuckers for folding endwise projecting portions of the wrapper against the ends of the piece, and means for forcing each partially wrapped piece through the bottom opening of each folding box and folding the final end portions of the wrapper against the ends of the piece.

12. In a wrapping machine, a frame having thereon a horizontal rotary circular table having a plurality of upwardly open trough shaped folding boxes at regular spaced intervals therearound, means for imparting intermittent progressive movements to the table and boxes, means for bringing a wrapper adjacent a given position to which each folding box is successively brought by the table, across the top of the box, means for bringing a piece to be wrapped to position on the wrapper over a box, and further and respective means supported by the machine frame independently of the table, and relatively to which each folding box on the latter is successively moved, for forcing the wrapper and piece into the folding box, upturning

the wrapper sides; for horizontally folding the opposite portions of the wrapper upstanding above the folding box horizontally onto the piece; for downwardly folding portions of the wrapper horizontally projecting endwise beyond the piece against the end of the latter; and for inwardly tucking opposite side portions of the wrapper endwise projecting beyond the piece against the end of the latter.

13. In a wrapping machine, a frame having thereon a horizontal rotary circular table having an annular marginal portion provided with a plurality of upwardly open trough shaped folding boxes at regular spaced intervals therearound, means for imparting intermittent progressive movements to the table and boxes, means for bringing a wrapper adjacent a given position to which each folding box is successively brought by the table, across the top of the box, a vertically reciprocating plunger located adjacent one of the positions of the folding boxes, for forcing the wrapper and piece into the folding box, upturning the wrapper sides, and oppositely located horizontal slides, mounted on portions of the frame inside and outside of the annular marginal portion of the table, at a farther position to which a box is brought, movable inwardly over and away from over the box top, and means for moving said slides.

14. In a wrapping machine, a frame having thereon a horizontal rotary circular table having an annular marginal portion provided with a plurality of upwardly open trough shaped folding boxes at regular spaced intervals therearound, means for imparting intermittent progressive movements to the table and boxes, means for bringing a wrapper adjacent a given position to which each folding box is successively brought by the table, across the top of the box, a vertically reciprocating plunger located adjacent one of the positions of the folding boxes, for forcing the wrapper and piece into the folding box, upturning the wrapper sides, and oppositely located slides, mounted on portions of the machine frame inside and outside of the annular portion of the table, at a farther position from the plunger, and around to which the table and box are brought, said slides having tuck folding members at their approached portions located between the planes of the bottom and top of the box, and means for moving said tucker slides horizontally crosswise of the trough opening in the box.

15. In a wrapping machine, a frame having thereon a horizontal rotary circular table having an annular marginal portion provided with a plurality of upwardly open trough shaped folding boxes at regularly spaced intervals therearound, the opposite side walls of said boxes having apertures therethrough between the intermediate and end portions, means for imparting intermit-

- tent progressive movements to the table and boxes, means for bringing a wrapper adjacent a given position to which each folding box is successively brought by the table, across the top of the box, a vertically reciprocatory plunger located adjacent one of the positions of the folding boxes, for forcing the wrapper and piece into the folding box, upturning the wrapper sides, oppositely located slides, mounted on portions of the machine frame inside and outside of the annular portion of the table, at a farther position from the plunger, and around to which a box carrying portion is brought, both of the slides having separated tuck folding members at their approached portions located between the planes of the bottom and top of the box and adapted to enter through, and be withdrawn from, said box side apertures, and means for moving said tucker slides horizontally transversely relatively to the folding box.
16. In a wrapping machine, a frame having thereon a horizontal rotary circular table having an annular marginal portion provided with a plurality of upwardly open trough shaped folding boxes at regularly spaced intervals therearound, means for imparting intermittent progressive movements to the table and boxes, means for bringing a wrapper adjacent a given position to which each folding box is successively brought by the table, across the top of the box, a vertically reciprocatory plunger located adjacent one of the positions of the folding boxes, for forcing the wrapper and piece into the folding box, upturning the wrapper sides, oppositely located horizontal slides, mounted on portions of the frame inside and outside of the annular marginal portion of the table, at a farther position to which a box is brought, movable inwardly over and away from over the box top, and means for moving said slides, and a vertically reciprocatory plunger additional to, and at a position remote from the first named plunger movable transversely relatively to the folding box and operable to downwardly turn upper endwise projecting portions of the wrapper against the end of the piece, means for reciprocating said plunger, another pair of oppositely located slides, mounted on portions of the machine frame inside and outside of the annular box carrying portion of the table at a position farther around from that of said first named slides and around to which the box on the table is brought, both of said latter slides having separated tuck folding members at their approached portions, located between the planes of the bottom and top of the box, and means for moving said tucker slides horizontally toward and from each other transversely relatively to the folding box.
17. In a wrapping machine, a frame having thereon a horizontal rotary circular table having an annular marginal portion provided with a plurality of upwardly open trough shaped folding boxes at regularly spaced intervals therearound, means for imparting intermittent progressive movements to the table and boxes, means for bringing a wrapper adjacent a given position to which each folding box is successively brought by the table, across the top of the box, and further and respective means supported by the machine frame, independently of the rotary table and relatively to which each folding box on the latter is successively moved, for forcing the wrapper and piece onto the folding box, upturning the wrapper sides, horizontally folding the opposite portions of the wrapper upstanding above the folding box horizontally onto the piece, downwardly folding portions of the wrapper horizontally projecting endwise beyond the piece against the end of the latter, and inwardly tucking opposite side portions of the wrapper endwise projecting beyond the piece against the end of the latter.
18. In a wrapping machine, a frame having a horizontal top, a vertical stud, supported by, and projecting above, said top, and having a stationary circular frame section supported at an upper part of said stud, a horizontal rotary circular table journaled about said stud, having an annular upstanding marginal portion, surrounding the edge of said circular frame section, provided with a plurality of upwardly open trough shaped folding boxes at regularly spaced intervals therearound, means for imparting intermittent progressive movements to the table and boxes; means for bringing a wrapper adjacent a given position to which each folding box is successively brought by the table, across the top of the box, and further and respective means supported by the machine frame, independently of the rotary table and relatively to which each folding box on the latter is successively moved, for forcing the wrapper and piece onto the folding box, upturning the wrapper sides, horizontally folding the opposite portions of the wrapper upstanding above the folding box horizontally onto the piece, downwardly folding portions of the wrapper horizontally projecting endwise beyond the piece against the end of the latter, and inwardly tucking opposite side portions of the wrapper endwise projecting beyond the piece against the end of the latter.
19. In a wrapping machine, the combination with a rotary table having a folding box, of a horizontal slide G, cam operating and spring retracting mechanism for reciprocating said slide in a plane approximately coincident with the top of the folding box, and means for imparting intermittent rotational

- movements to the table to position the folding box thereon in coöperative relation to said slide.
20. A wrapping machine in combination with a rotary table having a trough-shaped folding box thereon, of a vertically reciprocatory plunger frame provided with a depending plunger for coöperation with the folding box, a wrapper folder slideable transversely relatively to the folding box and connection between the plunger frame to said folder whereby the latter has its sliding movements imparted thereto in conjunction with the movements of the plunger frame. 70
21. In a wrapping machine the combination with a rotary table having a trough-shaped folding box thereon, of a vertically reciprocatory plunger frame provided with a depending plunger having separated lower members, a pair of transversely slideable wrapper folders oppositely operable adjacent and transversely of the path of movement of the folding box on the progressive table, a rotary shaft having a cam thereon and a cam rod engaged therewith and connected to one of said slideable folders, and a bar pivotally connected to the plunger frame and to the other of said slideable folders and having a toggle-like action imparted thereto by the reciprocatory movements of the plunger frame. 75
22. In a wrapping machine the combination with an intermittently movable table having thereon an upwardly open folding box constructed with pairs of apertures through its opposite sides, of oppositely operable slide bars having separated tucking folders movable through the apertured sides of the folding box, and means for imparting reciprocating movements to said slide bars. 80
23. The combination with an intermittently rotatable table provided with a plurality of trough-shaped folding boxes thereon, each having a pair of apertures through each side thereof, of a vertically reciprocatory plunger frame provided with a depending plunger H recessed at its lower end, a pair of slideable folders oppositely operable transversely of the length of one folding box and near the plane of the top thereof, an oppositely operable pair of tucking folders at the position of another of the boxes and having separated folding members arranged for movements through pairs of said apertures, cam actuated means for respectively operating the slideable folders which are at one side of the path of movement of the folding boxes, and means actuated by the plunger frame for actuating the slideable folders which are at the other side of the path of the boxes. 90
24. In a wrapping machine the combination with an intermittently movable rotary table having a plurality of trough-shaped folding boxes thereon, of a vertically reciprocatory plunger frame provided with a plun- 95
- ger, coacting with one of the folding boxes, a pair of oppositely operable folders for tucking side portions of a wrapper for a piece in one of the folding boxes, leaving endwise projecting portions of the wrapper at the bottom of the box, a gummer comprising depending gumming members, and having its location near and above one of the folding boxes, pivotally hung to the plunger frame, gumming rollers adjacent the gummer, and means for alternately swinging said gummer to positions, to gum the endwise extending portions of a wrapper in a box and to contact on the gum supplying roll. 100
25. In a wrapping machine, the combination with a progressive table having a folding box thereon, of a stationary abutment 98 and gum supplying rolls 100, a vertically reciprocatory plunger frame having a fork-shaped depending gummer pivotally hung thereon and provided with an angular lever like extension 97 formed and arranged for co-action with the said abutment for the purposes set forth. 105
26. In a wrapping machine the combination with a rotary table having a folding box constructed with an apertured bottom, and a slide, provided to the folding box, having an aperture, and normally closing the box bottom of a cam relatively to which the box and its slide are brought by the table operable to force the slide to bring its recessed portion coincident with the folding box aperture. 110
27. In a wrapping machine the combination with a rotary table having a folding box constructed with an apertured bottom, and a slide, provided to the folding box, having an aperture, and normally closing the box bottom, of a cam relatively to which the box and its slide are brought by the table operable to force the slide to bring its recessed portion coincident with the folding box aperture, and means operable adjacent a portion to which the box is moved for forcing the piece therein downwardly through the opened apertured bottom thereof. 115
28. In a wrapping machine, the combination with a rotary table having a folding box constructed with an apertured bottom, and a slide, provided to the folding box, having an aperture, and normally closing the box bottom, of a cam relatively to which the box and its slide are brought by the table operable to force the slide to bring its recessed portion coincident with the folding box aperture, and means beyond the location of said cam, and relatively to which the box is moved, for imparting a bottom-closing movement to said slide. 120
